UNITED STATES PATENT OFFICE.

MAX RALL AND ROBERT MAIER, OF STUTTGART, GERMANY, ASSIGNEES TO ROBERT BOSCH AKTIENGESELLSCHAFT, OF STUTTGART, GERMANY.

ELECTRIC SWITCH FOR HEAVY ELECTRIC CURRENTS.

Application filed February 10, 1922. Serial No. 535,550.

To all whom it may concern:

Be it known that we, MAX RALL and ROBERT MAIER, both citizens of Germany, residing at Stuttgart, Germany, have invented certain new and useful Improvements in Electric Switches for Heavy Electric Currents, of which the following is a specification.

This invention relates to electric switches intended for heavy electric currents and of the general type employing a switch bridge movable toward and from spaced stationary contacts, the switch bridge having metal brushes and also spring-pressed carbon brushes that are conductively connected with each other and project slightly beyond the contact surfaces of the metal brushes so as to effect the first contact on the closing movement of the switch bridge and the final interruption of the circuit on the opening movement of the switch bridge.

Our invention relates more particularly to certain improvements in switch bridges of the type shown in the patent to Kratz 1,311,974, dated August 5, 1919. With the known switch bridges, of the type shown in the aforesaid patent to Kratz, the carbon contacts are attached to plate springs which conduct the current, and there may be special steel plate springs increasing the strength of the elastic pressure to which the carbon contacts are subjected when in engagement with the stationary contacts of the switch. This arrangement does not remain effective for its intended purpose under all conditions of use, because at rather great intensities of current and upon a rather prolonged closure of contact the comparatively thin springs become heated to their glowing point and lose their elasticity.

The present invention relates to a switch bridge in which the before-mentioned drawback is obviated by providing a rigid carrier of conductive material and of relatively large mass and surface area for the carbon contacts, which carrier is guided upon the switch spindle and is itself subjected to an elastic pressure.

As, with this construction, direct contact of the springs with the highly heated carbons is avoided, the springs engaging the rigid carrier only there is not that conduction of heat from the carbons to the springs occurring in the known arrangement. To further lessen the conduction of heat to the

springs, our invention contemplates an arrangement providing for the engagement of the springs with the carrier only at points relatively remote from the carbons. Furthermore, the carrier may have a large sectional area for the current and a great radiating surface whereby the springs are especially effectively protected from undue heating. In order to permit of adjusting the carbon contacts into any position, the carrier in which they are mounted is preferably loosely guided upon the switch spindle.

In order to make our invention more clear, we refer to the accompanying drawing which shows, by way of example, one form of construction of the improved switch bridge, and in which similar numerals of reference denote similar parts throughout the several views. Figure 1 is an axial section through the switch bridge, and Figure 2 is a plan of the same. The switch bridge consists of the metal brushes 3 which bridges the stationary contacts 1 and 2. The carbon contacts 4 and 5 are affixed to a carrier 6 loosely guided upon the spindle 7. The carrier 6 is acted on by a plate spring 8. The carrier 6, in the example shown, is disk or plate-shaped in order to have a large radiating, i. e. cooling, surface. The size of the carrier renders possible the employment of a comparatively extended spring 8 of the configuration shown. This spring contacts with the carrier only at two oppositely disposed points 90° from the two oppositely disposed carbon contacts 4 and 5, measured along the periphery of the carrier 6, and which points are therefore at the maximum possible distance from the carbons 4 and 5.

To provide for the limited contact referred to of the spring 8 with the carrier 6, oppositely disposed ridges 9 may be formed either by appropriate bulgings of the spring 8 or by lugs upon the plate 6. The object of guiding the carbon carrier loosely upon the switch spindle is to allow of the surfaces of the carbons accommodating themselves more easily to the contact surfaces 1 and 2.

Having now described our invention, what we claim as new and desire to secure by Letters Patent of the United States is:

1. A switch bridge for heavy electric currents comprising, in combination, a switch

spindle, a conductive bridge member mounted thereon, metal brushes carried by said bridge member, a rigid conductive carrier member guided for movement in opposite directions upon said spindle, contacts upon said carrier member extending substantially in the direction of said brushes and adapted in one direction of movement of said carrier member to be projected beyond the terminal faces of said brushes, and a spring arranged to press said carrier member in the direction projecting said contacts.

2. A switch bridge for heavy electric currents comprising, in combination, a switch spindle, a conductive bridge member mounted thereon, metal brushes carried by and extending from one face of said bridge member, a conductive and disk-shaped rigid carrier loosely mounted on said spindle for movement in opposite directions therealong toward and away from said bridge member, carbon contacts on said carrier extending substantially in the direction of said brushes, said carrier being arranged for movement in one of said directions to project said carbon contacts beyond said brushes and for movement in the opposite direction to retract said carbon contacts and a spring pressing said carrier in the direction to project said contacts.

3. A switch bridge for heavy electric currents comprising, in combination, a switch spindle, a conductive bridge member mounted thereon, metal brushes carried by and extending from one face of said bridge member, a conductive and disk-shaped rigid carrier member loosely mounted on said spindle for movement in opposite directions toward and away from said bridge member and having spaced carbon contacts extending substantially in the direction of said brushes, said carbon contacts being adapted in one of said directions of movement of said carrier to be projected beyond the terminal faces of said brushes and a spring member mounted on said spindle and engaging said carrier at opposite points spaced a maximum distance from said carbon contacts to press said carrier in the direction to project said carbon contacts beyond said brushes.

4. In an electric switch for heavy currents, the combination with spaced stationary contact members, of a conducting bridge adapted for perpendicular switching movements relative to said stationary contact members and comprising a spring-plate

member provided with contacts for engagement with said stationary contact members, a rigid carrier member and contacts carried thereby for engagement with said stationary contact members, means mounting said carrier member upon said spring-plate member for vertical movement with respect to said spring-plate member and a spring arranged to press said carrier member toward said spring-plate member.

5. In an electric switch for heavy currents, the combination with spaced stationary contact members, of a conducting bridge member adapted for perpendicular switching movements relative to said stationary contact members and comprising a spring-plate member having metal brushes extending substantially in the direction of the switching movement, and a conducting circuit-breaking member having contacts at its ends normally projecting beyond said metal brushes toward said stationary contact members, said circuit-breaking member comprising a rigid contact carrier, means mounting said contact carrier on said spring-plate member for independent vertical movement and a spring arranged to press said carrier member toward said spring-plate member.

6. In an electric switch for heavy currents, the combination with spaced stationary contact members, of a conducting bridge adapted for perpendicular switching movements relative to said stationary contact members and comprising a spring-plate member provided with metal brushes for engagement with said stationary contact members, a rigid carrier member of conducting material and contacts carried thereby for engagement with said stationary contact members and means resiliently mounting said rigid carrier member with respect to said spring-plate member, whereby in the perpendicular movements of said bridge said contacts on said carrier engage said stationary contact members earlier and are disengaged therefrom later than the respective engagement and disengagement of said metal brushes with and from said stationary contact members.

In testimony whereof we have affixed our signatures in presence of two witnesses.
